US0D1079505S

(12) **United States Design Patent** (10) **Patent No.:** **US D1,079,505 S**
(45) **Date of Patent:** **** Jun. 17, 2025**

(54) **VOLTAGE METER**

(71) Applicant: **Dongguan Leyi Intelligent Technology Co., Ltd.**, Guangdong (CN)

(72) Inventor: **Jingyuan Wang**, Guangdong (CN)

(73) Assignee: **Dongguan Leyi Intelligent Technology Co.**, Dongguan (CN)

(**) Term: **15 Years**

(21) Appl. No.: **29/992,199**

(22) Filed: **Mar. 6, 2025**

(30) **Foreign Application Priority Data**

Feb. 18, 2025 (CN) 202530069557.X

CLAIM

The ornamental design for a voltage meter as shown and described.

DESCRIPTION

FIG. 1 is a perspective view of a voltage meter showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the voltage meter and form no part of the claimed design.

1 Claim, 8 Drawing Sheets
